UNITED STATES PATENT OFFICE

127,488

DESIGN FOR A FLUORESCENT TABLE LAMP

John F. Livers, Decatur, Ill., assignor to Faries Manufacturing Company, Decatur, Ill., a corporation of Illinois

Application December 21, 1940, Serial No. 97,523

Term of patent 7 years

To all whom it may concern:

Be it known that I, John F. Livers, a citizen of the United States, residing at Decatur, in the county of Macon and State of Illinois, have invented a new, original, and ornamental Design for Fluorescent Table Lamp, of which the following is a specification, reference being had to the accompanying drawing, forming part thereof, in which the figure is a perspective view of a fluorescent table lamp showing my new design.

I claim:

The ornamental design for a fluorescent table lamp, as shown.

JOHN F. LIVERS.
